UNITED STATES PATENT OFFICE.

GEORGE GODDU, OF WINCHESTER, AND FRED L. MACKENZIE, OF BEVERLY, MASSACHUSETTS, ASSIGNEES TO UNITED SHOE MACHINERY CORPORATION, OF PATERSON, NEW JERSEY, A CORPORATION OF NEW JERSEY.

SAFETY DEVICE.

Original application filed March 28, 1923, Serial No. 628,234. Divided and this application filed February 27, 1928. Serial No. 257,494.

This invention relates to safety devices and particularly to devices for enabling clutch-operated, power-driven machines to be safely turned over by hand while the power is on.

In various kinds of machines, for example, machines for operating upon shoes, it is necessary, in making certain adjustments and repairs, to turn the machine over by hand.

10 An example of such a machine is the welt butting and tacking machine disclosed in our application Serial No. 628,234, filed March 28, 1923, of which this application is a division. In this and similar clutch-

15 operated, power-driven machines it is necessary at times, in order to make adjustments or repairs, to turn the machine over by hand while the factory power is on. It is, of course, impracticable to shut down the

20 factory and inconvenient to remove the driving belt. A handle or wrench is provided for turning the shaft of the machine by hand, and devices have been provided for rendering the clutch inoperative. Prior to

25 our invention, however, it has been possible to apply the handle or wrench whether or not the clutch had been rendered inoperative and hence, if the operator neglected to render the clutch inoperative before applying

30 the handle or wrench, the machine might be put in operation by depression of the starting treadle by some one either accidentally or with malicious intent, such action being liable to result in injury to the operator or to the machine or both.

An object of the present invention is to provide a safety device, adapted for use in clutch-operated, power-driven machines of the type referred to, which will render it impossible to apply an implement such as a handle or wrench for turning the machine over by hand unless and until engagement of the driving and driven clutch elements has been rendered impossible.

45 Accordingly, as herein illustrated in its application to a welt butting and tacking machine of the type disclosed in the application above mentioned, the invention provides a safety device for rendering the machine clutch inoperative, which device comprises a pin having a thumb head which is slabbed off at one side. The construction is such that when the pin is turned so that

its slabbed-off side is next to the shaft, the clutch is rendered inoperative even if the 55 treadle is depressed. In this position of the pin head a handle or wrench can be applied to a shaft by which the machine is driven and the machine turned over thereby with safety, it being impossible to set the clutch 60 accidentally or otherwise. When the head of the pin is turned to other positions, the clutch is rendered operative and, since full-sized portions of the head are then next to the shaft, it is impossible to apply the handle 65 or wrench to the shaft so as to turn it.

In the drawings,

Fig. 1 is a perspective view of a portion of a machine in which the present invention is embodied, and

70 Fig. 2 is a side elevation, partly in section, of parts shown in Fig. 1.

Referring to Fig. 1, a welt butting and tacking machine, organized as set forth in the application above referred to, is operated 75 by a treadle 10 depression of which pulls downwardly on a treadle rod 12 connected by a pin 14 to an arm 16 carried by a shaft 18. Depression of the treadle swings the arm 16 into engagement with the forward 80 end of a lever 20 fulcrumed on a fixed stud 22 projecting from a portion 24 of the frame of the machine. The rear end of the lever 20 has pivoted thereto an upright arm 26, the upper end of which is held by a spring 85 28 against a member 30 which rotates with a shaft 32 by which the machine is driven. The arm 26 is embraced by bifurcations on an arm 34 of a sleeve 36 loose on a pin 38 projecting from the frame. On the sleeve 90 36 is a stop arm 40, which, at the end of a cycle, engages a clutch arm 42 and swings it into the position shown against a spring 44 (Fig. 2). In this position of the clutch arm the shaft 32 and the member 30 are 95 disconnected from continuously driven parts including a member 46 which is fixed to a sleeve 48 surrounding the shaft 32 and carrying a spiral gear 50 which is continuously driven when the factory power is on. The 100 clutch arm 42 is fast to a clutch pin 52 which extends inwardly and cooperates with recesses 54 formed on the inner periphery of the member 46 which forms the driving clutch member. The clutch pin 52 is cut 105 away or slabbed off on one side at 56 so that

when the clutch arm 42 is horizontal the pin 52 is freed from the recesses 54. When the clutch arm 42 is freed by the stop arm 40 the spring 44 swings the clutch arm 42 downwardly and rotates the clutch pin 52 to cause it to engage one of the recesses 54 to connect the driving element 46 with the driven element 30 on the shaft 32.

On the arm 26 is a block 58 which, upon upward movement of the rear end of the lever 20 by depression of the treadle, engages the arm 34 and swings the stop arm 40 away from the clutch arm 42 which then is swung down by the spring 44 to set the clutch. As the member 30 rotates, a projection 60 carried by it engages the arm 26 and swings it to release the block 58 from the arm 34, allowing the sleeve 36 to be rotated by a spring 62 to restore the stop arm 40 to a position to engage the clutch arm 42 and release the clutch when rotation of the driven shaft 32 is completed. The stop arm 40 carries a latch 64 which engages a notch 66 beneath the clutch arm 42 and prevents reverse movement of the shaft 32. The spring 28 is arranged to pull in a downward and rearward direction between a pin 68 on the arm 26 and a pin 70 projecting rearwardly from the fixed stud 22 so that the arm 26 is held toward the member 30, and the arm 26, as well as the rearward arm of the lever 20 to which it is connected, will be moved downwardly when the treadle pressure is released. Movement of the lever 20 is limited by a pin 72 on a projection of the lever which engages a hole in the frame 24.

In order that the machine may safely be turned over by hand while the power is on, means shown in Fig. 2 is provided for rendering the clutch arm 42 inoperative. A spring pin has a milled head 74 which is slabbed off at one side and has a transverse pin 76 extending through it, which pin engages slots of one depth when the head of the pin is in the position shown in Fig. 2 and, when the pin is pulled out by its head 74, turned 90 degrees and released, the transverse pin 76 engages slots of a greater depth, allowing a projection 78 on the inner end of the pin to lie in the path of a tail 80 formed on the clutch arm 42, which projection then prevents the arm 42 from turning to set the clutch, even if the stop arm 40 is thrown out of engagement with the clutch arm 42. In this position of the head 74 the slabbed-off side is toward the shaft 32 so that a suitable wrench may be placed over a hub 82 fixed to the shaft 32 and engaged with teeth 84 to turn the shaft 32 by hand. In the normal position of the head 74, it is in the way of the application of the wrench so that the operator has to turn the head, thereby rendering the machine safe to be turned over by hand,

before he can apply the wrench to the hub 82 so as to turn the shaft 32.

Having thus described our invention, what we claim as new and desire to secure by Letters Patent of the United States is:

1. In a power-driven machine having a clutch operable to connect driven parts with a source of power, a safety device for permitting the machine to be turned over by hand while the power is on comprising a rotatable pin and a member movable to effect connection between the driving and driven members of the clutch, said pin being constructed and arranged so that in one position of its rotation it will prevent movement of the movable member to set the clutch and permit application of an implement to turn the machine over and in another position of its rotation it will permit operation of the movable member to set the clutch and prevent application of said implement.

2. In a power-driven machine, a safety device for permitting the machine to be turned over by hand while the power is on comprising a rotatable spring-pressed pin, means for holding the pin in different positions of rotation, a slabbed-off head on said pin by which it may be released and rotated, a driving member, a driven member, rotatable means for connecting the driving member to the driven member, a hub on the driven member to which a wrench may be applied to turn the machine by hand only when the head of the pin is positioned with its slabbed-off side toward the hub, and means on the pin for preventing movement of said rotatable means when the pin is so positioned.

3. A power-driven machine having a clutch operable to connect driven parts with a source of power, a device for permitting the machine safely to be turned over by hand while the power is on comprising driving elements, driven elements including a shaft having a hub to which an implement may be applied by turning the shaft by hand, means for connecting the driving and driven elements, movable means located adjacent to said hub and constructed and arranged so that when placed manually in one position the connecting means is rendered inoperative to connect the driving and driven elements and the implement can be applied to the hub and when said movable means is placed in another position said connecting means is rendered operative and the implement can not be applied to the hub to turn the shaft.

In testimony whereof we have signed our names to this specification.

GEORGE GODDU.
FRED L. MACKENZIE.
